(57) **CLAIM**

The ornamental design for a receptacle terminal, as shown and described.

DESCRIPTION

FIG. 1 is a first perspective view of a receptacle terminal showing our new design;

FIG. 2 is a second perspective view of a receptacle terminal showing our new design;

FIG. 3 is a third perspective view of a receptacle terminal showing our new design;

FIG. 4 is a fourth perspective view of a receptacle terminal showing our new design;

FIG. 5 is a top view of the receptacle terminal of FIGS. 1-4;

FIG. 6 is a bottom view of the receptacle terminal of FIGS. 1-4;

FIG. 7 is a left side view of the receptacle terminal of FIGS. 1-4;

FIG. 8 is a right side view of the receptacle terminal of FIGS. 1-4;

FIG. 9 is a front side view of the receptacle terminal of FIGS. 1-4; and,

FIG. 10 is a rear side view of the receptacle terminal of FIGS. 1-4.

The receptacle terminal is used to conductively secure a wire to terminal pin of a vehicle latch.

References to “right side”, “left side”, “top”, “bottom”, “front” and “rear” in the figure descriptions are not meant to

(Continued)

require certain in-use orientation, a receptacle terminal according to the claimed design may be used in any orientation.
